UNITED STATES PATENT OFFICE.

JOHN I. McDONALD, OF ST. JOSEPH, MISSOURI.

COMBINATION-GARMENT.

1,269,945.

Specification of Letters Patent. Patented June 18, 1918.

Application filed October 1, 1917. Serial No. 184,246.

To all whom it may concern:

Be it known that I, JOHN I. McDONALD, a citizen of the United States, residing at St. Joseph, county of Buchanan, and State 5 of Missouri, have invented certain new and useful Improvements in Combination-Garments, of which the following is a specification.

This invention relates to combination garments and, more particularly, to combination 10 overalls.

My object is to provide an improved combination garment, especially adapted for use as an overall, embodying a jacket and trousers 15 detachably fastened together to obtain all the advantages of a union, or one-piece, garment, wherein the jacket overlaps the pockets in the trousers and has its skirt detachably fastened in such manner that the 20 pockets have their mouths covered, thereby preventing articles from falling out of them and dirt, or foreign substances, entering them, and minimizing the possibility of the pockets catching on any object.

Another object is the provision of a combination garment having an improved connection between the jacket and the trousers which is completely covered when they are worn, thereby affording a neat and dressy 25 appearance while permitting quick and easy detachment of the trousers whenever desired and also enabling the trousers to be worn separately from the jacket and held up by a belt or suspenders when the jacket is not 30 needed or the weather is too warm for its use.

It is within the scope of my invention to fasten the skirt of the jacket to the trousers at as many points as desired or to dispose 40 the fastenings in the region of any desired pockets which the said jacket is to cover but I, preferably, dispose the fastenings in the region of the side pockets of the trousers and allow the skirt of the jacket to freely overlap 45 the rear trousers pockets. Any suitable fastening devices may be used at the selected points, and also for connecting the jacket to the trousers waist band, although I prefer to employ buttons and buttonholes.

50 Preferably the connection between the trousers waist band and the jacket comprises a buttonhole strip sewed to the inside of the jacket above the lower edge of the skirt thereof and running all the way around 55 the same, and buttons on the waistband of the trousers. The waistband of the trousers

may be, and preferably is, provided with belt loops, enabling a belt to be used to hold up the trousers if they are used separately, as in warm weather. The buttons on said 60 waist band, however, enable the user to employ suspenders on such an occasion. When the entire garment is used, the trousers are held up by their connection with the jacket.

The invention is of particular utility when 65 embodied in overalls as all of the advantages of a one-piece overall are had with none of the disadvantages thereof. In the present garment the trousers and jacket may be put on or taken off separately, the jacket thrown 70 open while still connected to the trousers, or, the trousers taken down while the jacket remains on the wearer.

Closing the pockets by fastening the lower portion of the jacket over their mouths is of 75 particular utility when the wearer is working in a stooping, or flat, position, such as would be assumed when working around, or under, an automobile, for instance, as articles cannot fall out of the pockets or dirt 80 gain access thereto.

One embodiment of the invention is fully described hereinafter and shown in the accompanying drawings but as the details thereof may be changed, such disclosure is to 85 be considered as illustrative, rather than restrictive, of the scope of the invention.

In the accompanying drawings:

Figure 1, is a front view showing the 90 garment in use;

Fig. 2 a rear view thereof;

Fig. 3, a front view, partly broken away, the jacket being partly unbuttoned and thrown back;

Fig. 4, a rear view, partly broken away, 95 the skirt of the jacket being raised and the waist band partly unbuttoned;

Fig. 5, a detail side view, showing the skirt of the jacket raised; and

Fig. 6, a similar view, showing the jacket 100 buttoned down over the pockets at one side and the rear of the garment.

The invention is shown as embodied in overalls, having a jacket 1 and trousers 2. The jacket may be provided with any suitable pockets 3, as usual, and the trousers may have hip pockets 4, in addition to the side pockets 5.

The jacket is provided with a freely projecting buttonhole strip or band 6 which 110 is located on its inside face well above the lower edge of its skirt portion 7 and is

2
preferably connected thereto by stitching 8. This strip or band 6 runs all the way around the inside of the jacket, as an endless piece, to where it terminates at the front, as at 9, in the region of the front closure 10 of the jacket.

The jacket may be cut away at the front, as at 11 but its skirt portion 7 is of sufficient length, considered vertically, to cover 10 the side pockets 5, as shown in Figs. 1 and 6, and to overlie and cover the mouths of the hip pockets 4, as shown in Figs. 2 and 6, so that all of the pockets are sealed, as it were.

15 Buttons 12 on the waistband of the trousers are adapted to be buttoned into the buttonholes 13 in the strip or band 6. The trousers waist band may also be provided with belt loops 14 for the use of a belt if 20 the trousers are worn alone. The buttons 12 are arranged for the convenient application of the usual suspenders if the user prefers them to a belt when wearing the trousers alone.

25 The buttons 12 and strip 6 constitute a separable connection by which the trousers are held up by the jacket without requiring additional suspending means and they enable the trousers to be taken down, 30 quickly and easily whenever desired. Furthermore, the detachability of the trousers and jacket enables them to be readily put on and taken off, thereby eliminating the discomfort and stretching and pulling 35 required in putting on or taking off a union garment, even though it is detachable at the front while permanently fastened at the back.

At suitable points on the trousers, preferably in the region of the side pockets 5, there are provided fasteners, preferably buttons, 15 for fastening down the skirt of the jacket, as by the use of buttonholes 16 thereon, so that said jacket will be securely 45 fastened over the mouths of the pockets. It is to be understood that I do not limit myself to the location of the buttons 15, as shown, as they may be differently disposed, and additional ones may be used.

The purpose of the invention, in that respect, is to provide means for detachably fastening the lower portion of the jacket over the pockets so that they will be closed and covered to prevent articles from falling out and foreign matter from gaining access thereto. At the same time, merely unfastening one or more of the buttons 15 enables the wearer to gain access to one or more pockets. When the buttons 15 are located at the sides of the trousers, as shown in the 60 drawings, they are readily accessible but they, or other, fastenings for this purpose may be disposed farther to the front or farther to the rear of the garment.

Having thus described my invention, 65 what I claim as new and desire to secure by Letters Patent, is:

1. A combination garment comprising a jacket, trousers having side and hip pockets which are overlapped by the skirt of the 70 jacket, means connecting the jacket and trousers together, and separate means for fastening the skirt of the jacket to the trousers below the connection aforesaid, whereby the mouths of all the hip and side 75 pockets may be sealed by the skirt portion of the jacket.

2. A combination garment comprising a jacket, trousers having side pockets which are overlapped by the skirt of the jacket, 80 means detachably connecting the jacket and trousers, and separate means for detachably fastening the skirt portion of the jacket over the mouths of the side pockets aforesaid.

3. A combination garment comprising separate jacket and trousers, the latter having side pockets which are overlapped by the skirt of the jacket, means detachably connecting the jacket and trousers, and 90 means for fastening the jacket to the trousers in the general region of the hip portions thereof so that the lower portion of the jacket will cover the mouths of the side pockets.

In testimony whereof I hereunto affix my signature.

JOHN I. McDONALD.
